UNITED STATES PATENT OFFICE.

ALBERT L. WEBB, OF CLINTON, IOWA.

CIGAR-HOLDER.

SPECIFICATION forming part of Letters Patent No. 291,115, dated January 1, 1884.

Application filed June 29, 1883. (No model.)

To all whom it may concern:

Be it known that I, ALBERT L. WEBB, a citizen of the United States of America, residing at Clinton, in the county of Clinton and 5 State of Iowa, have invented certain new and useful Improvements in Cigar - Holders, of which the following is a specification, reference being had therein to the accompanying drawings.

10 My invention consists of a cigar-holder having concave jaws hinged together and adapted to readily receive and securely hold a cigar of any size, and provided with a curved tube constructed and arranged to receive and conduct to the mouth-piece the smoke in a cool condition and free from nicotine, avoiding the necessity of clipping off the end of the cigar and preventing it from becoming saturated with saliva, as hereinafter fully set forth.

15 In the drawings, Figure 1 is a side elevation of the holder. Fig. 2 is a longitudinal section. Fig. 3 is a cross-section on dotted line $x-x$ of Fig. 1, showing the position of the pointed end of the curved tube.

20 A A' are the concave jaws, hinged or pivoted together at a , and provided with the spring b , constructed and arranged in the jaws to hold them in a closed position.

25 B is a curved tube attached to the jaw A, and having its end b' extended into the mouth-piece C. The other end, c , of the tube is pointed, to adapt it to be readily inserted through a cigar, and the portion near the pointed end is provided with an opening, d , and this portion of the tube is extended transversely through the jaws, in position for the smoke from the cigar to enter the opening and to be conveyed through the tube to the mouth-piece. The holder is provided with a conic-shaped ferrule or cap, f , constructed to fit

30 closely at its inner end over the tube, and to receive and fit closely at its outer end over the inner end of the mouth-piece. The jaws being opened by pressure upon the projecting end h of the jaw A', as shown in dotted lines 45 in Fig. 1, a cigar, E, is inserted between jaw A' and the pointed end c of the tube, and as the jaws are closed, the pointed end of the tube pierces and passes through the cigar, placing at or near its center, on cross-section, the 50 opening d , through which the smoke from the lighted cigar enters, and is conveyed by the tube in a cool condition and free from nicotine, to the mouth-piece of the holder, avoiding the necessity of clipping off the end of the 55 cigar, and preventing it from becoming saturated with saliva.

55 In smoking, as the fire approaches the mouth of the jaws, the cigar may be moved outward in position to be entirely consumed.

60 It is evident that by means of the hinged jaws the holder is adapted to readily receive and securely hold cigars of all the various sizes which are usually made.

65 What I claim as new, and desire to secure by Letters Patent, is—

A cigar-holder consisting of the hinged jaws A A', spring b , mouth-piece C, and the tube B, provided with the opening d near its pointed end, which is extended transversely through 70 the jaws, the other end of the tube being connected with the mouth-piece, substantially as and for the purposes described.

75 In testimony whereof I affix my signature in presence of two witnesses.

ALBERT L. WEBB,

Witnesses:

S. J. BISHOP,
A. R. POTTER.
